UNITED STATES PATENT OFFICE.

EDWIN M. ROSENBLUTH, OF PHILADELPHIA, PENNSYLVANIA.

DESIGN FOR A MEMBER FOR LAMP-BRACKETS.

SPECIFICATION forming part of Design No. 32,166, dated January 30, 1900.

Application filed July 3, 1899. Serial No. 722,766. Term of patent 7 years.

To all whom it may concern:

Be it known that I, EDWIN M. ROSENBLUTH, of Philadelphia, in the State of Pennsylvania, have invented and produced a new and useful Design for a Member of a Lamp-Bracket, whereof the following is a specification, reference being had to the accompanying drawings.

My invention is peculiarly applicable to a bracket arranged to be secured upon a vehicle-frame to support a lamp in detachable relation therewith.

Figure 1 is a top plan view of a bracket member conveniently embodying my new design. Fig. 2 is a side elevation of the bracket member shown in Fig. 1.

The material feature of my design consists in the bracket-body A, having the member B offset, substantially in plane therewith, and provided at its extremity with the stud 20 C, projecting at substantially right angles to said plane.

Having described my invention, what I claim as new, and desire to secure by Letters Patent, is—

The design for a member of a lamp-bracket as herein shown and described.

EDWIN M. ROSENBLUTH.
